UNITED STATES PATENT OFFICE.

HANS CHRISTIAN LUCK, OF TELLURIDE, COLORADO.

AIR-BRAKE APPLIANCE.

No. 833,534.

Specification of Letters Patent.

Patented Oct. 16, 1906.

Application filed April 27, 1906. Serial No. 313,948.

To all whom it may concern:

Be it known that I, HANS CHRISTIAN LUCK, a citizen of the United States, and a resident of Telluride, in the county of San Miguel and State of Colorado, have invented a new and Improved Air-Brake Appliance, of which the following is a full, clear, and exact description.

The invention relates to air-brake appliances such as shown and described in Letters Patent of the United States No. 814,974, granted to me March 13, 1906.

The object of the present invention is to provide a new and improved air-brake appliance designed to automatically set the brakes in the train in case any one of the cars in the train moves out of normal position either by derailment or on account of a broken axle, broken arch-bars, or other causes.

The invention consists of novel features and parts and combinations of the same, which will be more fully described herein-after and then pointed out in the claims.

A practical embodiment of the invention is represented in the accompanying drawings, forming a part of this specification, in which similar characters of reference indicate corresponding parts in all the views.

Figure 1 is a plan view of a car-truck provided with the improvement, the car-body being shown in dotted lines. Fig. 2 is an enlarged sectional side elevation of the improvement on the line 2 2 of Fig. 1. Fig. 3 is a transverse section of the same on the line 3 3 of Fig. 2. Fig. 4 is a similar view of the same on the line 4 4 of Fig. 2. Fig. 5 is a sectional plan view of the same on the line 5 5 of Fig. 3, and Fig. 6 is an enlarged cross-section of the improvement on the line 6 6 of Fig. 1.

The train-pipe A of a fluid-pressure brake of the Westinghouse or other type and secured to the under side of the car-body B of a car is provided with a branch pipe C, normally closed by a plug-valve D, having a casing D' and a plug D², adapted to move axially to allow the escape of air from the branch pipe C and the train-pipe A to apply the brakes in the usual manner. The branch pipe C adjacent to the plug-valve D is supported in a frame E, attached to the under side of the car-body B, and the longitudinal bore of the plug-valve D is closed at the outer end by a plug E', fixed on the framework E. By reference to Fig. 5 it will be seen that when the plug D² is moved axially in the direction of the arrow a' then the air

can escape from the branch pipe C and the train-pipe A by way of the casing B' and its outlet D³. The outer end of the plug D² is provided with a pivoted stem D⁴, connected 60 by a short chain or a similar flexible connection D⁵ with a transverse pin D⁶, held in the forked end F' of a bar F, carrying at its forked end F' a plate F², preferably made square and seated on a seat E², formed on 65 the frame E. A spring G, coiled on the stem D⁴ and resting at one end on a washer G', abutting against the rear face of the seat E², presses with its other end on a shoulder D', formed on the stem D⁴, so that the plug D² is 70 normally held in a closed position on its seat in the casing D'. When, however, a side-wise, up or down movement is given to the bar F, then the square plate F² swings on the seat E² as the corresponding side, top, or bottom of the plate then forms a fulcrum, and consequently the bar F by the flexible connection D⁵ exerts a pull on the stem D⁴ to move the plug D² axially into an open position 75 to allow the escape of air from the branch pipe C and the train-pipe A. The plate F² is normally held to its seat E² by springs H, coiled on bolts H', attached to the plate F², the springs H resting at their forward ends on the back of the seat E² and abut with 80 their rear ends on washers H', held adjustably on the bolts H' by the nuts H³ thereof, so that the tension of the springs H can be regulated.

The forward end of the bar F terminates in 90 a vertical arm F³, on which are adjustably secured horizontally-disposed arms F⁴ and F⁵ by the use of pins F⁶, each engaging one of a series of apertures F⁷, formed on the upper and lower terminals of the vertical 95 arm F³. This forward end of the bar F is engaged by the members I' and I² for a fork I, attached to a rod I³, secured to a bolster of the car-truck B', so that when the latter assumes an angular position relative to the 100 car-body B then the fork I on account of being a permanent fixture of the truck moves with the latter and consequently engages either the vertical arm F³ or the upper or lower horizontal arm F⁴ or F⁵ to move the 105 bar F in a corresponding direction, whereby the plug D² is withdrawn, as previously explained, and air escapes from the branch pipe C and the train-pipe A to actuate the air-brake mechanism in the usual manner with a 110 view to setting the brakes to bring the train to a stop. The members I' and I² of the fork

I are adjustably secured in a bar I³ by a set-screw I⁴ to bring the members I¹ and I² the desired distance apart with a view to allow the truck to readily pass around sharp curves 5 or to move a short distance up or down relative to the car-body without the corresponding member I¹ or I² striking the vertical arm or either of the horizontal arms F⁴ or F⁵. Thus the car can readily pass around sharp 10 curves without danger of the air-brakes being automatically applied by the device above described, and the car-truck can also have a short up-and-down movement relative to the car-body without setting the 15 brakes, it being understood that the angle of position of the car-truck relative to the car-body must be more than that assumed by the train going around a sharp curve or more than the ordinary up-and-down movement of the car relative to the body for the device to automatically set the brakes, as above described.

From the foregoing it will be seen that whenever the car-truck assumes an abnormal 25 position relative to the car-body then a quick application of the brakes by means of the air-brake system is caused, so that a train is automatically brought to a standstill within a comparatively short time, and 30 consequently serious damage to the train and to the road-bed is entirely prevented.

It is understood that each car is provided with two of the device described, one for each truck, so that when either a front or rear 35 truck assumes the abnormal position referred to then the brakes are applied to bring the train to a standstill.

The head of the set-screw I⁴ is engaged by a suitable lock J, (see Fig. 2,) to prevent the 40 set-screw I⁴ from working loose.

Having thus described my invention, I claim as new and desire to secure by Letters Patent—

1. An air-brake appliance for automatically setting the brakes of a car in a train, 45 comprising actuating means on the car-truck, a valve adapted to discharge air from the train-pipe, spring-actuated mechanism adapted to normally close said valve, and a universal connection between said actuating 50 means and the said valve adapted to open the latter on a car moving in any direction out of its normal position in the train.

2. An air-brake appliance for automatically setting the brakes of a car in a train, 55 comprising a fork fixed on the car-truck, a valve for discharging air from the train-pipe, spring-actuated mechanism adapted to normally close said valve, and means connected 60 with said valve and controlled by the said fork for opening the valve on the fork moving vertically or horizontally beyond a predetermined angle.

3. An air-brake appliance for automatic-

ally setting the brakes of a car in the train, 65 comprising a fork fixed on the car-truck, a valve for discharging air from the train-pipe, and a spring-pressed connection capable to swing sidewise and up and down, the said connection being controlled by the said fork 70 and connected with the said valve to open the latter on the fork moving the said connection sidewise, up or down beyond a predetermined angle.

4. An air-brake appliance for automatically setting the brakes of a car in the train, 75 comprising a fork fixed on the car-truck, a valve for discharging air from the train-pipe, a rectangular seat on the car-body, and a spring-pressed plate normally seated on the 80 said seat and having a shank connected with the stem of the said valve, the shank having vertical and transverse arms adapted to be engaged by the said fork on the latter moving beyond a predetermined angle in a sidewise, 85 up or down direction.

5. An air-brake appliance for automatically setting the brakes of a car in the train, comprising a fork fixed on the car-truck, a valve for discharging air from the train-pipe, 90 a rectangular seat on the car-body, and a spring-pressed plate normally seated on the said seat and having a shank flexibly connected with the stem of the said valve, the shank having vertical and transverse arms 95 adapted to be engaged by the said fork on the latter moving beyond a predetermined angle in a sidewise, up or down direction.

6. An air-brake appliance for automatically setting the brakes of a car in the train, 100 comprising a fork fixed on the car-truck, a valve for discharging air from the train-pipe, a rectangular seat on the car-body, a spring-pressed plate normally seated on the said 105 seat and having a shank flexibly connected with the stem of the said valve, the shank having vertical and transverse arms adapted to be engaged by the said fork on the latter moving beyond a predetermined angle in a sidewise, up or down direction, and a spring 110 for holding the valve to its seat.

7. An air-brake appliance for automatically setting the brakes of a car in the train, comprising actuating means on the car-truck, a plug-valve for discharging air from 115 the train-pipe on pulling the plug axially into an open position, and a connection between the said plug and the said actuating means for pulling the plug open on the car moving out of its normal position in the train. 120

In testimony whereof I have signed my name to this specification in the presence of two subscribing witnesses.

HANS CHRISTIAN LUCK.
